UNITED STATES PATENT OFFICE.

MARYAN B. BARSZCZEWSKI, OF CLEVELAND, OHIO.

DEMOUNTABLE RIM.

1,416,440.

Specification of Letters Patent. Patented May 16, 1922.

Application filed March 19, 1921. Serial No. 453,765.

To all whom it may concern:

Be it known that I, MARYAN B. BARSZCZEWSKI, a citizen of the United States, residing at Cleveland, in the county of Cuyahoga and State of Ohio, have invented certain new and useful Improvements in Demountable Rims, of which the following is a specification.

This invention relates to demountable rims 10 of that type composed of articulated sections, some of which may be broken or collapsed inwardly for the purpose of releasing a tire mounted on the rim.

The object of the invention is to provide 15 an improved construction for holding the ends of the collapsible sections in expanded position.

The invention is illustrated in the accompanying drawings in which Figure 1 is 20 a vertical section of part of a rim provided with the invention. Fig. 2 is a plan of Fig. 1. Fig. 3 is a longitudinal section showing the manner of "breaking" or assembling the parts. Fig. 4 is a perspective view of one 25 end of the collapsible sections. Fig. 5 is a perspective view of one of the ends of the main rim section. Fig. 6 is a perspective view of the end of one of the locking sections opposite to that shown in Fig. 4. Fig. 30 7 is a perspective of the end of the other locking section which cooperates with that shown in Fig. 6.

In the drawings, 1 indicates the main section of a rim part of which is cut away to 35 receive the locking or collapsing sections 2 and 3. Each end of the rim section 1 has a rectangular opening 4 with an inwardly offset bar 5 extending across part of it near the rear end of the opening. The strip 5 may be either pressed out of the rim or fastened to it. One end of each of the sections 2 and 3 has a hooked projection 7 which fits in 40 the opening 4, the end 8 of the projection engaging behind the bar 5, as clearly shown in Figs. 1 and 2. The other end of the section 2 has an extending tongue 9 which is off-set inwardly from the surface of the section, as shown at 11, and is notched or reduced to form a neck 11^a and head 12 which is thicker than the tongue and forms an outwardly projecting part or catch 12^a. The cooperating section 3 is provided with a slot 13 through which the head 12 and tongue 9 may be inserted, under a cross-bar 14 at the

end of the section, said cross-bar being offset inwardly from the surface of the section, thereby forming a sort of sliding hinge joint, and when the parts are expanded the tongue rests under the crossbar 15 of the opposite section as shown in Fig. 1, and the head 12 fits in locking engagement in a hole 16 in the section 3, where it may be fastened by a turnbutton 18.

By releasing the button 18 and inserting a proper tool at the joint, the sections 2 and 3 may be broken or collapsed inwardly as shown in Fig. 3, this action being permitted by the flexible connection provided by the hooked extensions 7 and the opening 4. The rim can then be easily placed in a tire. Then the locking sections are forced outwardly to complete the circle and expanded within the tire until the head 12 drops into the hole 16, which completes the ring. The connection is such that the rim sections cannot become accidentally separated, and the device provides a very efficient means for easily applying the rim to a tire or removing the same therefrom.

I claim:

1. A demountable rim comprising a main section having its ends separated, two intermediate sections interchangeable with either one of said ends of the main section, each end of said main section being provided with a cross bar secured to the rim at its ends only, one end of each intermediate section being provided with two recesses, one of said recesses arranged for engaging said bar, while the other recess engages the end of the rim of the main section.

2. In a demountable rim having a plurality of sections, a separable hinge joint comprising two flat cross bars on one rim end separated therefrom by slots, one of the said cross bars being depressed toward the axis of the rim, and the other flush with the rim base, a projection on the other rim end having a recess on the outer side adapted to receive one of the cross bars and a recess on the inner side to receive the other cross bar.

In testimony whereof, I affix my signature in presence of two witnesses.

MARYAN B. BARSZCZEWSKI.

Witnesses:

JOHN A. BOMMARDT,
BESSIE F. POLLAK.
